GYRO TOY

Peter Amato, Brooklyn, N. Y.

Application December 11, 1946, Serial No. 715,546

1 Claim. (Cl. 46—50)

1 This invention relates to toys wherein a prime mover delivers energy for causing the desired movement of a traveller-element. In carrying out the invention, the principle of the gyroscope is used, and by virtue of the precessional and other characteristics of gyroscope operation, the traveller-element is given a manner of movement which is instructive and attractive.

The movement of said element is instructive because a child, and even the average adult, may by visual observation obtain considerable insight into such modern marvels of man's use of physical laws as the gyroscopic compass for safe peace-time navigation and the expedients whereby in national defense a combat means such as the atom bomb may be subjected to an automatic control whereby the target may be hit even when thousands of miles away.

There is in the present invention an interesting and valuable interaction between, on the one hand, the internal gyroscopic torque developed and responsible for the precessional behavior of a gyroscope (that is, the precessional couple or precessional torque), and, on the other hand, the fact that the gyroscopic element itself is mounted to spin in such manner that its spin-mounting is displaced along its spin-axis for a considerable distance beyond the physical limits of the gyroscopic element from the precession axis. An elongate member having a universal pivoting means intermediate its ends which permits said member to turn about a vertical axis and which at the same time permits said member to dip at one end from the horizontal may be and desirably is employed to allow for such displacement; the gyroscopic element is carried near one end of said member and in such relation thereto that the spin-axis extends substantially along the general length of extension of said member, and the aforesaid traveller-element is carried by said member near the other end thereof.

When, as is now preferred, the traveller-element is a miniature airplane, its movements are so controlled by the new gyroscopic prime mover for a propellable toy such as is provided by the present invention, that the airplane while captive yet in flight moves at different speeds, rises as for a take-off, glides as for a landing, and dives and zooms. As for these latter, a characteristic of operation of the preferred embodiment of the toy herein disclosed, is that with the gyroscope-element rotating at various of certain speeds the airplane, while traversing its circular path of travel, alternately zooms or climbs up-

ward somewhat sharply and dives somewhat sharply. The angles of climb and zoom, moreover, may be modified as desired and what may be called ground-speed or distance travelled per unit interval of time may also be modified as desired, and this according to various energy-additions to the toy applied manually and by choice as and when desired during rotation of the gyroscope-element.

10 10 The prime mover is for the purpose of spinning the gyroscope-element. This spin may be effectuated in various different ways and by various different means.

The spin may be imparted by continued delivery of energy to said element from a stored source of energy, for instance, a wound up spring.

The spin, again, may be started and maintained by substantially instantaneous delivery to the gyroscope-element of a store of energy, for instance, by whipping to unreeled condition a string, cord or other flexible member reeled on the shaft of the gyroscope-element or on a pulley fixed on said shaft. These last mentioned methods of prime mover action can serve to cause initial rotation of the gyroscope-element at an exceedingly high rate of speed, which gradually decelerates as the imparted momentum is slowly dissipated.

In further exemplification of the invention, the gyro-element may be spun continuously or intermittently or by a series of repeated power impulses conducted as long as desired and all without handling the gyro-element as in the two embodiments of the invention already referred to. This operation will be by remote control as by way of an electric motor housed in a hollow casing, with such motor and the casing constituting the gyro-element, and with certain auxiliaries added, as, for instance, a pair of slip-rings

40 acting in tandem to conduct current to the motor despite the peculiar movements of the main movable part which at or near one end carries the gyro-element and at or near its opposite end carries the airplane. This main movable part is a long, preferably slender rod or wand, desirably of some slight inherent elasticity for a reason which will later be explained.

This wand, as it will be called, serves to maintain the airplane in captive flight. In other words, the airplane travels through an endless path, and since this path may have a multiplicity of variations as to its general plane and in other respects, but nevertheless is always centered about a support for the wand, the latter is mounted intermediate its ends about two points

of pivoting. That is, the wand is not only preferably a lever of the first class with a fulcrum intermediate its ends but is also preferably given a universal pivotal mounting. In that case, and with an electric motor used as above, two slip-rings will be of value as aforesaid for energizing the motor while overcoming the difficulty of using conducting wires which by-pass the support carrying the universal mounting for the wand.

For further comprehension of the invention, and of the objects and advantages thereof, reference will be had to the following description and accompanying drawings, and to the appended claim in which the various novel features of the invention are more particularly set forth.

In the accompanying drawing forming a material part of this disclosure:

Fig. 1 is a view in perspective of one embodiment of a toy constructed in accordance with this invention.

Fig. 2 is an elevational view, partially in section, the cutting plane being indicated in Fig. 1 by the line 2—2.

Fig. 3 is an enlarged detail view in perspective.

Fig. 4 is, on a further enlarged scale, a section taken on the line 4—4 of Fig. 3.

Fig. 5 is a perspective view, showing the gyro-element of Figs. 1—4.

Fig. 5A is a portion of a diametral section of said gyro-element, to give details of construction not elsewhere illustrated.

Fig. 6 shows this embodiment, complete in side elevation.

Fig. 7 is a diagrammatic view, showing, on a comparatively minute scale, certain parts seen in Figs. 1—5, and illustrating in dot-and-dash lines what may be assumed to be the highest-level and the lowest-level circular paths of all the various paths of travel of the airplane, and also having other delineations to graphically illustrate the zone of possible travels of the airplane at heights above the wand when the latter is horizontal.

Fig. 8 is a schematic view, showing developments of said highest-level and lowest-level paths and showing also the development of an intermediate-level path.

Fig. 9 is a similar view, but with the developments last referred spread vertically, showing certain of the take-off angles which can be exhibited by the airplane, and a typical cruising path characterized by undulations with crests and troughs vertically displaced above and below the general line of forward travel of the airplane.

Fig. 10 is partially an end elevation of a gyro-element pursuant to another embodiment, one containing a clock spring, looking toward the face of the element remote from its connection with the wand; this view largely being a section taken on the line 10—10 of Fig. 11.

Fig. 11 is a diametral section taken through the stub-cylindrical casing of the gyro-element, with certain parts shown in elevation.

Fig. 12 shows the spring-winding key in perspective.

A gyro-toy made pursuant to the present invention as such toy is shown herein, comprises the combination of a rotor to act as a gyro-element, such as the element marked 20 in Figs. 1—6, a wand 21 on one end of which the element 20 is journaled for spinning about an axis of revolution aligned with the direction of longitudinal extension of the wand, a support 22 here shown as underlying the wand and so in the present case adapted to be placed on the floor or on a

tabletop or the like, a universal pivotal connection 23 between the wand and the top of the support at a point between the ends of the wand, and, on the other end of the wand, a miniature airplane 24.

The two gyro-elements shown in the drawings (the element 20, in the form of the invention shown in Figs. 1—9; and the element 25, in the form of the invention shown in Figs. 10 and 11) correspond in function; and one, as to the main casing formation, is in many respects a replica of the other.

Preliminarily it may be well to note certain structural features common to the casing characteristics of the gyro-elements 20 and 25. Referring first to the gyro-element 25, the same comprises, as shown in Figs. 10 and 11, a pair of fairly shallow cups 26 and 27, one snap-fitted into another as indicated at 30°, thereby to provide a casing stub-cylindrical in shape. The end walls of such casing are dished inwardly at 26' and 27' and then are arched outwardly as shown at 26'' and 27''.

Referring next to the gyro-element 20, as shown in Figs. 1, 5 and 6, here the casing employed is hollow except for a shaft 28 about which the gyro-element 20 is to revolve. At the side of the gyro-element which faces the universal connection 23 when the toy is assembled, shaft 28 is projected for some distance, as seen best in Fig. 5A, through and beyond a hollow pulley or reel 29. The reel adjacent its inner flange 29' may be secured to the casing in any convenient way; as, for instance, by spot welding. The part of the shaft 28 which enters the hollow gyro-casing after passing beyond reel 29 carries a sleeve 30 held in place by a nut 31 applied to a thread on the end of shaft 28 where it projects slightly beyond collar 30. These features are seen best at the lower part of Fig. 1 and such sleeve and nut coat with a collar 29'' (see Fig. 5A) fixed on the shaft within the hollow reel 29, to limit axial movement of the gyro-element.

Referring now more particularly to the embodiment of the invention illustrated in Figs. 1—9, which includes the gyro-element 20, a plurality of holes 32 are shown (Fig. 5) as cut in a face of said element, and serve to act siren-like to create a sound suggestive of the roar of an airplane propeller when the toy is operated.

The wand 21 is very long and slender and for a suitable distance at each end is bored axially to provide terminal sleeves. At a point intermediate its ends, and preferably much closer to its end on which the gyro-element (20 or 25) is to be mounted than its end on which the airplane 24 is to be mounted the wand is drilled laterally for mounting it on a horizontal pivot pin, shown at 36 in Fig. 4.

The ends of the pivot pin 36, which after passing through the wand 21 also passes through the tines of an upstanding fork 37, mount a pair of decorative additions 38 here made to resemble signalling lights on a tower at an airfield. These additions are strikingly suggestive of what they represent when conically hollowed out as shown in Figs. 3 and 4 and when lined with ordinary tin foil.

The parts 21, 36, 37 and 38 together with their permanently attached dependent pin 39 constitute a single removable unit for disassembling the toy for convenient packaging. The pin 39 provides the complementary part of the universal joint on which the wand is mounted, the pin 36 providing the horizontal pivot.

The gyro-element 20, details of which have been described above, is another disassemblable unit, the same being mounted on one end of the wand 21, by inserting its shaft 28 into a sleeve-carrying end portion of the wand. Such end portion, incidentally, is shown very clearly in Fig. 11. The dimensions are such that the shaft has a snug fit in the sleeve of the wand yet not too tight a fit to prevent ready removal of the gyro-element unit.

The support 22 is here shown as including a basal square 42 carrying a pyramidal post 43 at the top of which is a cap 44, upstanding from which is a block 45 drilled to rotatively receive the pin 39, providing the vertical pivot of the universal joint 23.

The miniature airplane is shown as a monoplane having the usual tail surfaces and at its nose a four-bladed stamped metal propeller loosely pivoted so that the propeller will revolve during flight of the airplane due to the relative wind.

Referring to Fig. 2, one of the wings 47 mounted on the fuselage 48 is cantedly offset from a rod 50 of about the same diameter as the shaft 28. The rod 50 is of a diameter to fit fairly tightly in the sleeve portion at the appropriate end of the wand 21, yet without too much tightness to prevent rotating the rod 50 in its receptor a sufficient amount to make changes in the angle of incidence of the wings 47 by manually grasping the fuselage and turning the same while the toy is idle. Thus the wings of the airplane may be given any desired climb or dive angle, to have its path of flight affected by interaction between gyroscope-precession and the angle of incidence of the wings.

Referring next to Fig. 7, only the part of the wand 21 between the universal joint and the airplane is shown and this merely diagrammatically. Also, all possible travels of the airplane with the wand inclined from the horizontal to lower the airplane are not considered. When centrifugal force is at its maximum, that is, when the gyroscope-element is fairly heavily weighted, and spinning at a high rate of speed, the wand will be held horizontal, and the airplane will have ground speed along the path indicated in dot-and-dash lines at 55. When the forces acting on the wand to cause the airplane to travel through an orbital path have become dissipated to a point where the universal joint will not allow the wand to droop at its end opposite to the airplane to a greater angle from the horizontal than that indicated in broken lines at 56, the airplane will have an orbital path such as that indicated in dot-and-dash lines at 57. Our assumption is that we are considering merely all the possible paths of forward movement of the airplane when the wand is in a horizontal plane or the airplane is above such plane in the toy as constructed.

Then the zone of possible multitudinous variations of forward travel of the airplane will be that included between the dot-and-dash lines 55 and 57 and the dotted lines 59 and 60; a zone, in other words, which may be defined as a truncated hemi-prolate-spheroid.

Referring next to Fig. 8, a development of the path 55 is shown at 61 and a development of the path 57 is shown at 62. In Fig. 7, the vertical dotted line 64 represents the vertical distance between the horizontal planes including the dot-and-dash circles 55 and 57. The mid-point on this line is marked 65 and a development of the orbital path of forward movement of the airplane when the latter is in the horizontal plane containing said mid-point is shown at 67 in Fig. 8.

In Fig. 9, the development 67 is fully shown, as is also the vertical line 64, while the developments 61 and 62 are fragmentarily shown. In Figs. 7 and 8 the arrowheads contained in the dot-and-dash circles 55 and 57 show the direction of forward travel of the airplane during spinning of the gyro-element in the direction indicated by the arrow 70 in Fig. 1. This spinning is set up by rapidly unreeling a string, cord or the like wrapped for a considerable number of turns around the reel 29 in such fashion that when unreeled, it is unwrapped from the reel in counter clockwise direction.

As soon as the cord or the like has wholly left the reel, the gyro-element, which meanwhile had been grasped, and particularly, when the gyro-element is given a slight manual thrust to cause it to travel in counter clockwise direction simultaneously with ungrasping the same, the gyroscope-precession force starts the airplane travelling through an orbit of circular travel such as that indicated by the dot-and-dash circle 55 (Fig. 7), the wand quickly inclining on its horizontal pivot to cause the airplane to rise and exhibit any one of the number of desired take-off angles, two of which are indicated at Fig. 9 at 73 and 74.

It will now be understood that if the initial speed of the gyro-element is not at its maximum, the take-off angle will be more like that indicated at 74 than at 73. When, on the other hand, the initial speed of the gyro-element is very high, the airplane will have a take-off angle more like that indicated at 73 than that indicated at 74.

Another interesting feature of the toy is that when, after a number of circular travels of the airplane, there is noted a tendency of the wand to slow down or even pause in its turning about its vertical axis, a slight finger thrust against the wand applied in the predetermined direction of its rotation, apparently releases energy still in the prime mover, and the wand resumes its rotation about its vertical axis.

The principle of nutation is involved. Consider the case of a gyro-wheel mounted as is the gyro-element of the present invention near one end of an elongate member or rod corresponding to the wand 21, with such member supported intermediate its ends on a universal pivotal mounting like that provided for wand 21, but with a counterpoise movable along the length of the arm of said rod opposite to the arm thereof carrying the gyro-wheel. By setting the counterpoise at different places on the rod, torques about a horizontal axis can be produced of different magnitudes in either the clockwise or the counter-clockwise direction. If the counterpoise is adjusted to counter-balance the gyro-wheel, and the latter is started spinning, precession will be exhibited, as is well known, by orbital movement of the gyro-wheel about the vertical pivot on which the rod is mounted, and during this orbital movement the rod will remain horizontal.

If, however, the counterpoise is adjusted on the rod to over-balance the gyro-wheel, on spinning the latter and then releasing the rod while holding it horizontal, the gyro-wheel will start precessing by moving through a horizontal path, and at the same time the end of the rod carrying the gyro-wheel will alternately dip and rise, so that the precessing is at uniform velocity. The consequent nodding of the spin-axis is known as nutation. Also, if the gyro-wheel is started spinning and then the rod released while held horizontal but now with the counterpoise balancing

the gyro-wheel, what happens is that there is no precession.

Any gyroscope exhibits nutation of the spin-axis on the sudden application of a torque; but the long arm of wand 21 on which traveller-element 24 is carried renders the nodding especially conspicuous. The amplitude of the nutational dip depends upon the amplitude and suddenness of development of the gravity torque. Nutation would continue indefinitely if there were no opposition to the dipping due to air or bearing resistance, as for example in the case of nutation of the earth's axis. In the case of most gyroscopes, the nutation is quickly damped to zero. Suppose that the gyro is spinning at constant rate in the clockwise direction as seen when viewed from the counterpoise toward the gyro. In addition, suppose that the position of the counterpoise is such that there is a torque in the clockwise direction about the horizontal pivot of the pivotal mounting for the rod; with, however, a zero torque about the vertical axis of said mounting.

At the instant the gyro-frame is released, there is zero precession, and the heavy end of the rod (here the end of wand 21 carrying the gyro-element 20 or 25) tilts downward below the horizontal. The tilting gives a vertical component of the angular momentum about the horizontal pivot, this directed downward. There being zero torque about the vertical pivot, any angular momentum must be generated about the vertical pivot at the same rate in the direction opposite to the vertical component just mentioned. This is developed by angular velocity (angular momentum) in a vertically upward direction. This precessional velocity is greater than that which would have been produced if the spin-axis had not been tilted so much.

The gyroscope has greater kinetic energy when precessing than when not precessing, though the total energy is constant. In order that the total energy may remain constant, the accelerated precessional velocity is accompanied by a rise of the end of the rod carrying the gyroscope. The inertia of the system carries the heavy end of the wand 21 above the equilibrium position.

As the potential energy is increased by the elevation of said end of the wand, the kinetic energy of rotation must decrease, that is, the precessional velocity must diminish. When the heavy end of the wand dips, the precessional velocity increases. When said heavy end rises, the precessional velocity decreases.

After a few oscillations, the spin-axis will remain at a nearly constant inclination to the vertical and the velocity of precession will remain nearly uniform. The inclination of the spin-axis from the vertical, at any instant, is the angle of nutation.

Referring now to the other one of the two illustrated of the many possible embodiments of the invention, and in this connection directing attention to Figs. 10, 11 and 12, the showing here is of a gyro-element which is given its spinning speed by unwinding of a suitable spring means previously wound so as to be placed under tension.

As already stated, the exterior of the gyro-element 25, here shown, is similar in most respects to that of the gyro-element 20 of Figs. 1-9. However, the gyro-element 25 is provided interiorly with various parts which will now be described.

A shaft 88, corresponding to the shaft 28 of 75

the first described embodiment for being fitted into the sleeve portion 89 at an end of the wand 21, such wand drilled as indicated at 90 for taking the horizontal pivot of the universal joint, extends only part way through the gyro-element's housing. An end portion of the shaft 88 enters a bore within a clutch member 92 and is riveted therein at 93, inside the gyro-element.

The spring 94 to be wound is shown as a band spring wound into a flat spiral as is typical of the main spring of a clock. The rivet 93 attaches one end of spring 94 to clutch member 92. The other end of the spring is secured as indicated at 95 to an annular weight-casting 96, when it is desired to give a weight-increment to the gyro-element.

The weight 96 is kept from slipping circumferentially of the interior of the gyro-element by a suitable number of long rivets or double-headed studs 97. For simplicity, and for balance, three of such studs are employed, spaced apart 120°. To facilitate registration of the apertures in the gyro-element housing and through the annular weight 96, so that the rivets or studs 97 may be quickly attached, the casting may be made to have a single outwardly projecting seat 96', and for keying with the same the casing 26 forming part of said housing may be dimpled as indicated at 26a.

Complementary to the circumferential series of clutch teeth on the disc like inner portion 92' of clutch member 92, are similarly arranged teeth on a disc like portion 98' of a clutch member 98. Seated in suitable recesses in clutch members 92 and 98 is an expansile coil spring 99.

Spring 99 normally maintains the two clutch members out of engagement. However, clutch member 98 carries a finger-tip receiving dished end-portion 98'' exterior to the gyro-element. When it is desired to wind up the spring 94, it is merely necessary to grasp the gyro-element say with the left hand and, after giving a fingertip pressure to the clutch member 98 by way of its end 98'', thus to couple the two clutch members, to insert the winding key 100 shown in Fig. 12 so that its finger 101 enters the bore 102 in clutch member 92 and its transverse blade 103 seats itself in a transverse slot 104 cut diametrically across the end of clutch member 92 where it projects beyond the casing 26 thereupon, proper turning of the key winds up the spring to the desired tension. Just after the key is withdrawn, pressure on the outer end of member 98 is released and the gyro-element ungrasped.

For a toy which should have a relatively low cost of manufacture, the clutch device, including its associated spring means, may be omitted, as there is not a great strain on the muscles of the hand in grasping the gyro-element with sufficient force to prevent it from turning while the spring is being wound up tightly. In various other respects, also, parts of the improvements may be used without others.

While I have illustrated and described the preferred embodiments of my invention, it is to be understood that I do not limit myself to the precise construction herein disclosed and the right is reserved to all changes and modifications coming within the scope of the invention as defined in the appended claim.

Having thus described my invention, what I claim as new, and desire to secure by United States Letters Patent is:

A rotatable toy comprising a wand having a

and a gyroscope mounted on the other end of said wand, means adjacent said gyroscope supporting said wand for universal movement, said gyroscope comprising a hollow circular casing having opposed, parallel end walls centrally apertured, said other end of said wand extending through said aperture formed in one of said walls to rotatably support said casing thereon, a clutch member formed on said other end of said wand and disposed within said casing, a shaft mounted in said aperture of the other of said end walls and extending on both sides thereof, the exterior end of said shaft having a diametric slot formed therein and the inner end thereof having a clutch member formed thereon, said first and second clutch members being oppositely disposed and normally spaced apart, resilient means for maintaining said clutch members in their normal positions, a helicoid spring having one of its ends secured to said casing and the other end affixed to said shaft, a manually operated key for insertion within said slot whereby said shaft may be rotated to wind said spring, and said casing being displaceable in the direc-

tion of the longitudinal axis of said wand to effect engagement of said clutch members during said winding operation.

PETER AMATO.
